UNITED STATES PATENT OFFICE.

JOHN S. TERRELL, OF MARSHALL, MISSOURI.

PADDLE-WHEEL.

SPECIFICATION forming part of Letters Patent No. 611,293, dated September 27, 1898.

Application filed November 27, 1897. Serial No. 659,994. (No model.)

To all whom it may concern:

Be it known that I, JOHN S. TERRELL, of Marshall, in the county of Saline and State of Missouri, have invented certain new and useful Improvements in Paddle-Wheels and Water-Wheels; and I do hereby declare the following to be a full, clear, and exact description of the invention, such as will enable others skilled in the art to which it appertains to make and use the same.

My invention is an improvement in paddle-wheels for propelling purposes.

My object is to construct a paddle-wheel having paddle-blades so arranged as to enter the water on edge or vertically, to remain vertical while being forced through the water, and to pass out of it vertically. Such a paddle-wheel's usefulness would consist, first, in saving the power now lost in forcing the paddle-blades into the water and lifting them out again when in use; second, as the proposed blades would at all times be vertical to the water they would exert a greater propelling force; third, as proposed blades would enter the water on edge no power would be lost, and in consequence the blades could be used deeper in the water, thus better utilizing the known fact that water resistance rapidly increases as depth increases.

The accompanying drawings, with this specification, are intended to fully describe and explain my alleged invention.

Figure 1 is a side elevation of paddle-wheel. Fig. 2 is a transverse section of Fig. 1.

In each of the figures, 1 indicates the paddle-blades, which are riveted or otherwise firmly fixed to shafts 2, which are journaled through and adapted to turn in wheel-rims 3, and have arms 4 firmly keyed or otherwise fixed onto their ends on outer sides of wheel-rims 3. These arms 4 thus become integrally a part of the paddle-blades, which must turn with the arms as they turn, and be thereby controlled by them, as hereinafter set forth. These arms 4 terminate in outwardly-extending horizontal journals 5, (see Fig. 2,) on which are journaled rollers 6, adapted to move in stationary cams 7. These cams are two in number to each wheel, are continuous, are identical in every particular, have inner and outer flanges throughout their entire circuit, and are so fastened to the inner sides of

wheel-house as to engage the rollers 6 between said flanges. The cams 7 being fixed and the arms 4 movable, it is evident that 55 the shape or curvature of the cams must control the position of the arms, and they in turn must control the blades when the wheel is rotated.

To illustrate the action of my improvement, it must be understood that the wheel is to be so placed on the vessel as to entirely submerge the lower paddle-blades. Beginning at A, Fig. 1, the blade has just reached the water-line W, and at b is entirely submerged. The lower section of each blade is slightly longer than the upper—i. e., the distance from shaft 2 to lower edge of paddle-blade is greater than from shaft to upper edge—and this fact tends to force the blade 70 to turn; but being fixed to shaft the turning action is transmitted to the arms 4, and thence to rollers 6, which are thus pressed against the inner flange of cam 7, along which they roll as the wheel revolves till c is reached. 75 At c the cams 7 are at such distance from wheel-rims 3 as to free the rollers 6 from the inner flanges, and the water-pressure forces them against the outer flanges, along which they roll till released from water-pressure at 80 e. From e they are held against outer flanges by gravitation till the reversing-point F is reached.

F is an upward bend of the cams into which the rollers pass and, striking against 85 their opposite sides, are held back till the blades are pointed forward in proper position to enter the water at A.

It will be readily understood that as both sides of wheel and cams exactly coincide the 90 wheel would reverse as well as go forward.

In the form of cam illustrated in Fig. 1 it is apparent that the lower edges of the blades 1 must pass over the upper edges of each succeeding blade at about e and of each preceding blade at about A when the wheel is 95 revolved.

Having thus described the construction and use of my alleged invention, I claim as new and useful the following and ask Letters Patent therefor:

In a feathering paddle-wheel, the combination of two identical, continuous, inwardly grooved or channeled cams, eccentric in shape,

to each paddle-wheel; cams having short upward lateral bend in center of larger end curve; cams rigidly fixed to inner sides of wheel-house on opposite sides of paddle-wheel and upwardly eccentric thereto with lateral bend of cams exactly above shaft of paddle-wheel; cams adapted to receive within their grooves friction-rollers; rollers journaled on outwardly-extending horizontal journals; journals extending from upper ends of perpendicular arms; arms firmly fixed at lower ends to horizontal paddle-blade shafts; shafts journaled through and adapted to turn

in rims of paddle-wheel; paddle-blades firmly fixed to said shafts between wheel-rims, parallel with before-mentioned arms and at a point a little above center of blades; all substantially as and for the purposes hereinbefore set forth. 15

In testimony whereof I have signed this 20 specification in the presence of two subscribing witnesses.

JNO. S. TERRELL.
